UNITED STATES PATENT OFFICE.

JOHN J. MEYER, OF NEW YORK, N. Y.

INSERTABLE JOINT.

Application filed June 25, 1921. Serial No. 480,294.

To all whom it may concern:

Be it known that I, JOHN J. MEYER, a citizen of the United States, and a resident of the city of New York, borough of Manhattan, in the county and State of New York, have invented a new and Improved Insertable Joint, of which the following is a full, clear, and exact description.

This invention relates to plumbing and has for an object to provide an improved insertable joint for soil pipes and the like wherein a repair job may be made with the use of a minimum amount of material and labor.

Another object of the invention is to provide an improved joint for soil pipes and the like wherein it will be possible to cut off a joint of pipe now in use and substitute one new section when inserting a Y, T or other new section.

A still further object of the invention is to provide an insertable joint for soil pipes and the like wherein means are presented which will present a proper support for the upper part of a soil pipe and at the same time elevate the bottom of the hub to a point adjacent the bottom of the lower end of the upper section of soil pipe.

In the accompanying drawing—

Figure 1 is a side view of part of a soil pipe with certain parts broken away for better illustrating the invention.

Figure 2 is a fragmentary sectional view showing the parts as they will appear when an inserted section is being placed in position.

Figure 3 is a view of the structure shown in Figure 2, but with the hub adjusted to its operative position and ready to receive the packing or filling.

Figure 4 is a view similar to Figure 2 but showing a modified form of the invention.

Figure 5 is a view similar to Figure 4 but showing a slight modified construction.

Referring to the accompanying drawing by numerals, 1 and 2 indicate flooring structures of a building through which the sections 3 and 4 of a soil pipe extend. If, for any reason, it should be necessary to remove the section 4 and place a new section in place, an entire soil pipe must be taken down and a new one substituted or one or more of the sections of pipe broken and removed and a joint supplied in addition to the new section 4. In the construction

shown in Figure 1, the section 5 indicates the new section provided with a joint at the upper end whereby it co-operates with the old section 6 previously secured to section 3. The section 4 may be readily set into the hub 7 of section 8 by merely placing the same correctly in position and then providing suitable packing for the hub. However, the section connecting section 4 and section 6 cannot be of the ordinary type as the hub of an ordinary section could not be properly fitted over the section 6 and then lowered into the hub 9 of section 4. To obviate this difficulty, a special insertable joint is provided in which section 5 is used, which section is a straight tube having threads 10 at the upper end onto which the hub 11 is threaded when the parts are in operative position. In order to raise the effective bottom of the hub 11 to the bottom of section 6, a filling ring or nipple 12 is provided which nipple is provided with a cylindrical section 13 of slightly less diameter interiorly and exteriorly than the section 6 and with a radiating flange 14. When the section 5 is being inserted the parts are positioned as shown in Figure 2 as said section is first inserted into hub 9 and then swung over to a position beneath the nipple 12. The hub 11 is then lowered and screwed onto the threads 10 and the joint is in condition for receiving packing which may be a fibrous filling 15 and then the lead filling 16 or may be of any other suitable material.

Figure 3 shows the parts ready for the filling and Figure 1 shows the parts after the filling has been inserted. This construction presents a tight connection and at the same time provides a support for the section 6 and other sections bent the same. In Figure 3 an aperture is provided in the hub 11 which is normally closed by the plug 17, said aperture acting as an inspection opening, to ascertain if there is a contact between the pipe 6 and nipple 12. If desired, a second aperture may be provided in the hub 11 for receiving an auxiliary vent or drain pipe 18 or if this pipe is not needed the plug can be inserted for closing the opening. An opening 18 is also provided in the nipple 12 so as to provide a free communication between the pipe 18 and the interior of the nipple. By providing the flange 14, it will be noted that the effective bottom of the hub is raised to substantially

the same plane as the bottom of section 6 whereupon the filling 15 or the lead filling 16 cannot move through the nipple of section 6.

5. In Figure 4, another form is provided in which the nipple is formed into a ring 22 having a less internal diameter than section 6 and also a less external diameter though the walls of the ring are of the same thickness and, therefore, present a proper support for section 6 and the other sections of pipe above said section. The bell 23 is used with this form of the invention, which bell is provided with a raised bottom 24 and a threaded bore portion 25. When the section 5 is being inserted, the threaded portion 25 is screwed upwardly until it is opposite the ring 22 whereby the section 5 may be readily inserted and then the hub is screwed down onto the section. As the shoulder 24 overlaps the lower end of section 6 after threads 25 have engaged pipe 5, the parts are properly bent together and aligned so that the packing may be readily inserted, which in this instance may be lead alone or fibrous packing with the lead on top of the same.

Figure 5 shows a form of invention similar to Figure 4. The bell 26 is provided with an upstanding flange 27 instead of the raised shoulder 24, which flange acts as means for centering the ring 22 and holding the same in place when the bell is screwed down onto section 5 as illustrated in the drawing.

40. In all forms of the invention, some form of supporting ring structure is provided which will act as a nipple or spanning ring and at the same time will act as a permanent support for the sections of pipe arranged above the joint. It will also be noted that in all forms of the invention, the hub is adjustable so as to readily permit the insertion of the lower pipe section 5 and then act as means for locking said section against lateral movement.

45. It is understood that the hub bottom may be modified and elevated as shown in Figure 5 so as to bring the hub bottom and pipe end 6 on the same plane or the hub bottom above pipe end 6 to cause a proper alignment thereof.

50. It will be noted that the spacer ring or rings form a false hub bottom. The rings may be arranged solid as shown in Figure 4 though this is not absolutely necessary as a flange structure similar to that shown in Figure 2 may be used, the straight hub allowing free movement over said nipple or ring for engagement or disengagement with the pipe section 5. In any of the forms of

the invention, the hub bottom may be placed at any point between pipe end 5 and pipe 6 to meet all conditions.

55. It is to be understood that a pipe having branch openings or the usual strengthening bead at the end opposite the threaded end of pipe section 5 is to be considered uniform in diameter throughout as well as an ordinary straight pipe within the meaning 60 of the specification and claims as these features have nothing to do with the functioning of the threaded end.

What I claim is:—

1. An insertable joint for soil pipes and 75 the like comprising two pipe sections of uniform diameters, a tubular nipple of less exterior diameter than the said two pipe sections inserted between said pipe sections, and a hub adapted to form a water tight 80 joint around the ends of the two pipe sections and nipple, one end of the hub being adapted for a filler joint, the other end being contracted and interiorly threaded to screw upon the threaded end of the other 85 pipe section, the contracted end of said hub being capable of telescoping over said nipple and movement of said nipple being limited by the superimposed pipe section.

90. 2. An insertable joint for soil pipes and the like, comprising a pipe section having threads at the upper end, a tubular supporting and spacing sleeve having a longitudinal portion of slightly less exterior diameter and a flange portion of greater exterior 95 diameter than the exterior diameter of said pipe section, a removable hub having an inwardly extending threaded portion adapted to be screwed onto said threaded section when in use and when said threaded section is being inserted to telescope over the smaller portion of said sleeve by reason of the reduced diameter of said smaller portion, said sleeve to rest on the end of the 100 pipe section.

105. 3. An insertable joint for soil pipes and the like, comprising two pipe sections, a tubular nipple of less exterior diameter than the said two pipe sections inserted between said pipe sections, and a hub adapted to form a water tight joint around the ends of the two pipe sections and nipple, one end of the hub being adapted for a filler joint, the other end being contracted and interiorly threaded to screw upon the threaded end of the other pipe section, the contracted end of said hub being capable of telescoping over said nipple and movement of said nipple being limited by the superimposed pipe 110 section.

JOHN J. MEYER.
